corporation of Massachusetts

Application March 31, 1952, Serial No. 19,121

Term of patent 14 years

(Cl. D14—30)

To all whom it may concern:

Be it known that I, Charles A. McLeod, a citizen of the United States of America, residing at the city of Birmingham, county of Oakland, State of Michigan, United States of America, have invented a new, original, and ornamental Design for a Vehicle Wheel Trim or Similar Article, of which the following is a specification, reference being had to the accompanying drawing, forming a part hereof, wherein:

Fig. 1 is a face elevational view of a vehicle wheel trim or similar article showing my new design.

Fig. 2 is a perspective view thereof; and
Fig. 3 is a cross sectional view taken along the line 3—3 of Fig. 1.

The dotted line showing in the drawing is for illustrative purposes only.

I claim:

The ornamental design for a vehicle wheel trim or similar article, substantially as shown and described.

CHARLES A. MCLEOD.
